UNITED STATES PATENT OFFICE

WYLIE G. WILSON, OF JERSEY CITY, NEW JERSEY, ASSIGNOR TO EVERLASTING VALVE COMPANY, OF JERSEY CITY, NEW JERSEY, A CORPORATION OF NEW JERSEY

ANGLE BLOW-OFF VALVE

Application filed August 31, 1926. Serial No. 132,840.

This invention relates to valves, particularly blow-off valves for steam boiler service, of the angle-type.

As is well known, the blow-off valve is from time to time opened to withdraw boiler water which has become too dense, and is also used to empty the boiler when desired; the valve being connected to the drain line at the level of about the lowest point in the boiler.

10 The blow-off valve thus is required to withstand probably more severe service conditions than almost any other valve. In the first place, the fluid being discharged by the valve passes from a confinement at high pressure to a zone at atmospheric pressure merely.

15 Naturally, the velocity of the fluid through the valve is high, as an accompaniment of the pressure drop. Such pressure reduction is precipitous, and represents an enormous force; especially where the drop is considerable, as in the case of high pressure boilers, in connection with which the present invention is of great value. The out-rushing fluid ordinarily carries in suspension par-

25 ticles of sharp, gritty matter of a highly abrasive character. There results what may be termed an abrasive scour of parts of the valve interior, particularly at the valve seat and its environs, but with seri-

30 ous scour also at other parts of the valve, especially where the valve is an angle-type valve, and the body or casing presents an abutment surface for the fluid stream to cause the latter to make approximately a right-hand 35 turn to approach the valve outlet.

One of the objects of the present invention is to provide a valve body or casing having an abutment surface of the kind last indicated, wherein such abutment forms a casing-wall 40 subdivision and wherein such casing-wall, at said subdivisions and its neighboring subdivisions, is so designed as to prolong the safe life of the valve. By safe life is meant the number of high-pressure stream-dis- 45 charge hours to which the valve may be subjected in service before the point is reached where there is no longer present the proper factor of safety, against valve breakage and the consequent danger of scalding an attendant. I have found that according to the pres-

ent invention, the new valve may have a very long safe life, if the abutment surface and the neighboring wall subdivisions are properly proportioned as to the average masses of the abutment and the neighboring wall subdivisions, to give a considerable average thickness to the abutment wall subdivision. I prefer to provide such mounting for the abutment surface wall, by employing solely therefor the aforesaid neighboring wall subdivisions and by making the latter of a certain thinness as compared with the thickness of the wall subdivision carrying the abutment surface.

Another object is to provide a valve where- 65 in the scalding faces at the valve outlet are protected against scour by the impact of the fluid being discharged under high velocity while carrying abrasive matter in suspension.

Another object is to provide a valve where- 70 in means are incorporated for preventing the trapping or pocketing of gritty accumulations or fluid anywhere at or in the vicinity of the valve outlet.

Another object is to provide a valve where- 75 in the sealing faces, and other surfaces at the valve outlet, are protected against damage from what is known in the art as the wire-drawing effect.

Another object is to provide a valve where- 80 in grit or the like deposited on the sealing faces, and particularly on the surface against which the movable valve member is seated, may not interfere with tight closure at any valve closing operation and at the same time 85 may not damage any of the sealing surfaces in such a way as to interfere with a tight closure at a subsequent valve closing operation.

Another object is to provide an angle valve 90 wherein the valve member carries a sharp edge which seals against the valve seat, but wherein said edge and seat are protected against non-tight valve closure, as the result of side thrust of the fluid against the stem or other moving valve part.

Another object is to provide a valve where- 95 in a plurality of sealing faces are carried by a movable valve part, which faces coact with other faces for conjoint action in effecting tight valve closure.

Various other objects and advantages of the invention will be specifically pointed out or will be apparent hereinafter, in the course of a description of a preferred one of the 5 various possible forms of the invention as shown in the accompanying drawing; it being understood, of course, that such form is merely illustrative of one combination and arrangement of parts calculated to attain the 10 objects of the invention, pursuant to present preference, and hence the detailed description of such form now to be given is not to be taken as at all defining or limiting the invention itself. That is to say, the scope of protection 15 contemplated is to be taken solely from the appended claims, interpreted as broadly as is consistent with the prior art, and with explanatory references to the specification only where a claim is ambiguous or to be 20 impliedly limited beyond its express terms to avoid such as are in order to save the validity of said claim.

In the accompanying drawing:

Fig. 1 is a view showing the valve stem in 25 side elevation and other parts of the valve in a section which is axial to the inlet and outlet openings or ports;

Fig. 2 is a fragmentary view, showing certain of the parts of Fig. 1 on a slightly enlarged scale, but showing the valve only 30 partly closed.

Fig. 3 is a horizontal cross sectional view through the casing.

The valve illustrated includes a fixed structure and a movable structure; the former including a valve casing 3, and the latter a valve stem 4, a valve head 5, a valve-closing ring 6, a threaded retainer 7 for said ring, and a threaded plug 8 sleeving the lower end of 40 the stem above its terminal enlargement 9.

The valve casing 3 is in the main a unitary casting, including an inlet 10, an outlet 11, and a casing proper incorporating a plurality of wall subdivisions 12 and 14.

45 The wall subdivision 12 presents inside the valve casing an abutment surface for giving the steam traversing the valve a right-angled change of direction, to direct the steam to make egress from the casing through a fixed 50 member 15 having an upper cup 16 and a reduced bore opening into the valve outlet 11.

Wall subdivision 12 is of a considerable thickness at its central part shown in section in Fig. 1; said wall 12 being reduced in thickness 55 so as to blend smoothly into the side walls 14. Preferably, these side walls are of about the thickness indicated at 14', from the points where they spring away from the plane containing the inner end of inlet 10, to the point, 60 such as that indicated at 14a, where they begin slightly to swell in the thickness to merge with the thickened subdivision 12. It will be noted that according to this arrangement each of the 65 comparatively thin wall subdivisions 14 has a rather considerable horizontal line of curva-

ture as compared with the similar line of the more massive subdivision 12 carrying the abutment surface 12a. I have found that such an arrangement prolongs very much the safe life of the valve; the wall subdivisions 14 70 coacting with the wall subdivision 12 to modify the shape of the latter and to hold its mass in location whereby said wall subdivision 12 may withstand safely gradual wear from the abrasive action of gritty particles in the fluid stream impinging against and deflected by the abutment surface 12a. In practice, I have found it desirable to proportion the thicknesses of these wall subdivisions so that the maximum thickness of a 75 subdivision 14 is approximately 5/7 of that of the subdivision 12.

The fixed member 15 is threaded into the valve casing as indicated and so as to make a fluid tight seal between itself and the casing, by compressing a ring gasket 17.

The sealing ring 6 is illustrated as relatively small in cross-sectional area, with the cross-sectional shape of the ring substantially that of a diamond. This shape produces 90 an upper edge 6a and a lower edge 6b, each in a single plane, with both planes parallel, and parallel to the plane containing the bottom wall of the cup 16 which carries the seating surface for the edge 6b. The cup 95 bottom wall, further, is parallel to the surface forming the roof of the annular recess 18 within which the ring is positioned and retained, but not tightly held, being loosely mounted so as to permit of slight play, by 100 surface contact with a cylindrical rib 5a depending from the valve head 5 and by surface contact with the conical rim portion of a bottom enlargement on retainer 7. The precise cross-sectional shape of the ring is 105 relatively unimportant. The important features are comparatively small cross-sectional area and sharp edges on both sides of the ring. In order to obtain a ring which shall operate according to the invention, including the ability to be shaped to present and retain for a considerable length of time edges on opposite sides of exceeding sharpness, the ring should be of some hard elastic material, such as bronze. The flexibility of 110 the material is important, as the ring is held in the recess 18 in such a manner as to be free to flex at different points around the same, and thus have movement relative to the other parts of the movable valve structure during 115 the final downward squeeze of the valve stem in closing the valve. The required right closure of the valve is obtained by the line contact of the edge 6b against the bottom wall of cup 16 and the line contact of edge 6a against 120 the annular surface forming the roof of recess 18.

I have found that when a sealing edge such as that shown at 6a or 6b is used, that is, a sealing edge on a ring, an effect is produced 125

quite different from the effect obtained when the sealing edge is on a rigid head. By putting such a sealing edge on a ring, which is flexible, and which does flex under pressure from the stem, and which, further, is somewhat loosely held, the ring adjusts itself to any slight inequalities in the sealing surface which it contacts. For instance, I have tested such a valve construction as that illustrated, wherein the sealing faces were not ground at all, and simply used as they were turned on the lathe; and I found that the valve was tight not only under 60 lbs. pressure, but also tight under 250 lbs., and even 500 lbs. I made not only one test but a multiplicity of tests with the same valve; and I found the seal had a tight life which was more than 40 times the tight life of a high grade standard valve with relatively wide coacting faces on disc and seat, when controlling steam at 500 lbs. pressure. Tight closing of the valve as just described I found could always be relied on merely by applying hand power, multiplied by the common screw thread connection between the valve stem and hand wheel, with such hand wheel of the usual diameter. Further, where grit is likely to be present, I find that the sharp edge pushes the grit aside and forms a clean metal-to-metal seal, while relatively wide faces crush the grit between them and cause leakage.

An important feature of the illustrated valve in this latter connection, is the mounting of the valve head loosely on the stem 4. This loose mount is obtained by having the plug 8 sleeve the stem with some looseness, by shaping the enlargement 9 to have a spherically rounded lower face, and by housing such enlargement loosely in chamber 19 roofed over by the bottom of plug 8 and having a plane bottom wall 5b, preferably parallel to the plane of the ring edges 6a and 6b. The result is that when the valve is almost closed and the edge 6b is forcing its way through a grit collection in the bottom of cup 16, some side sway is possible and the edge 6b may have a plowing or sweeping action on the grit.

This looseness of mount of the valve head on the valve stem, the retention of the ring on the head to give the former slight freedom of movement, and the capacity of the ring to flex definitely in different portions, all coact to insure tight valve closure, to give long life to the valve, and to accomplish these results regardless of the presence of grit between the relatively moving valve parts. Such a result is of course contributed to in an important degree by the arrangement whereby the substantially uniplanar edges 6a and 6b and the surfaces with which they contact are all substantially parallel and substantially perpendicular to the general line of movement of the valve head toward and away from the outlet 11.

Theoretically, an arrangement of the kind

described in the paragraph immediately preceding would not seem to require a guide for the valve head; even though such a guide is required in the type of valve heretofore constructed where the coacting sealing elements of the valve member and seat are both relatively wide surfaces. Actually, however, I have found that to produce a practical valve of the type herein disclosed, it is apparently necessary to provide a guide for the valve head. I have found in this connection that, due to the loose mounting of the valve head on the valve stem, the inrush of fluid acts transversely of the head to throw the latter at a slight angle to the horizontal at about the instant the edge 6b contacts with its coacting surface in the bottom of cup 15. This angle is often so great that when the stem is further screwed down, practically a point only on the edge 6b is in contact with the surface in the bottom of cup 16. This point bites into said surface and the ring, instead of sliding slightly across said surface to adjust itself into parallelism therewith, becomes clamped tighter and tighter thereagainst at a fixed angle of inclination thereto. In other words, in the absence of a guide or some equivalent restraining means to hold the valve head against a greater than the permissible degree of side-sway, there is not the required side-sway in one direction, the direction of approach of the fluid stream toward the surface 12a, and there is a fatal excess of side-sway in the opposite direction. I have found that best results are apparently obtained when, at the instant of sealing contact, the head is held to dispose the edges 6a and 6b almost parallel to the plane of the surface in the bottom of cup 16.

This guide I prefer to provide by constructing the valve-head as a cylindrical piston working in the cup 16 as a cylinder. When the valve is closed, as in Fig. 1, the peripheral portion 5c of maximum diameter on the valve-head is well down in the cup 16. After the valve is opened wide, the valve-head is, of course, well above the top of cup 16. Nevertheless, the head properly enters the cups when the head is moved toward valve-closing position. The fit of the stem 4 in the head, while loose enough to permit some side-play of the latter, is still sufficiently close to cause the head to make such entry. As the head travels down in the cup, the wide portion 5c and the fit of the same in the cup, combine to induce parallelism of the elements 6b and 21 prior to their actual contact. Also, the instant the relation of the parts shown in Fig. 2 is established, constriction of the fluid stream at the point 20 tends to equalize the pressure all around the valve-head at the level of such point.

Consequently, the plane of the edge 6b is substantially parallel to the bottom of the

cup 16 at and immediately before the instant of contact, yet the slight required side-play is provided whenever necessary on account of the presence of a grit particle or clump or other irregularity.

Said guide, in the present instance, forms a part of a means having important operative features, in that said means functions to prevent the accumulation of grit or other foreign matter anywhere within the cup 16 and on the working parts on or carried by the valve-head at its underside, as well as to prevent damage from the wire-drawing effect common to most if not all high-pressure steam-valves as heretofore constructed.

15 Said means is carried partly by the valve-head 5 and partly by the cup 16, more particularly as shapings thereof. The cup comprises an upstanding cylindrical wall which
20 curves into the flat seating surface surrounding the outlet port. Thus, on both sides of the limits of the possible edge contacts of the ring 6 with the bottom of the cup, that is, on both sides of the real valve seat for the
25 edge 6b, there are extensions of such seat imperceptibly merging therewith but considerably increasing the width of the same; said seat and both these extensions being uniplanar and parts of the cup bottom. In
30 addition, there are further outward extensions of such seat, one smoothly blending into the other and the latter smoothly blending into that one of the first-mentioned extensions outside said valve seat; such further
35 outward extensions being that indicated at 22 in Fig. 2, and beyond it, the cylindrical side wall of the cup 16.

As to the valve head 5, note that beyond the fifth side, or outer cylindrical wall, of the ring 6 which is engaged by the inner cylindrical surface of the depending rib 5a, the valve head has first some increase in diameter, due to the thickness of the said rib, then maintains this diameter for some distance above the bottom of the rib, until the bottom of the enlargement 5c is reached, and then the head has a greater increase in diameter, which latter diameter is maintained until the top of the enlargement 5c is reached.

Note further that the distance up along the rib is less than the distance up along the enlargement. Note also that the ring 6 has considerable protrusion below the bottom of the rib. The arrangement is such that with the parts as shown in Fig. 2, the bottom of the enlargement 5c is well above the bottom of the cup 16. In other words, when the enlargement has just entered the cup, as shown in Fig. 2, the edge 6b is at a greater perpendicular distance from the flat bottom of the cup than the outer cylindrical surface of the depending rib 5a is spaced in a radial direction from the cylindrical wall of the cup.

65 The operation of said means is as follows:

Assume that the valve closing operation had proceeded as far as shown in Fig. 2. No more grit can flow into the cup 16; but of course fluid can. This fluid flows through the constricted opening at the point 20, and thence as indicated by the arrows of Fig. 2. Consequently the fluid is gradually expanded while on its way to the outlet 11, rather than given the sudden, first, abrupt expansion at the outlet which is chiefly responsible for the wire-drawing effect. In the present valve no such effect is set up even between head portion 5c and cup 16. The cross-sectional area of the passage between elements 6b and 21 is much greater than between 5c and 16. When 6b and 21 approach each other so that the space between them is the same as the spacing of 5c and 16, the large surface or wide face of head portion 5c then overlapped by the side-wall of cup 16, causes constriction of the fluid stream and protects elements 6 and 21. When the head first enters the cup, however, there is greater spacing between the bottoms of elements 5c and 16 than between the bottoms of element 5a and 16; and as a result, any grit under the element 5c is washed out by the fluid flow through a free and unrestricted outlet. Thus it will be seen that the movable valve-closing structure with the walls carried thereby are so related to the chamber 16 with its chamber walls as to continuously provide, during movement of the valve sealing element 6 toward contact with the bottom of the chamber 16, a passage for the valve-traversing fluid, which decreases in cross-sectional area toward the port 11.

Finally, due to the fact that the bottom of the enlargement $5c$ on the valve-head is set well above the edge $6b$, such edge is always shielded from constricted fluid washing directly across the same. 105

Inasmuch as many changes could be made in the above construction, and many apparently widely different embodiments of my invention could be made without departing from the scope thereof, it is intended that all matter contained in the above description or shown in the accompanying drawing shall be interpreted as illustrative and not in a limiting sense. 110 115

It is also to be understood that the language contained in the following claims is intended to cover all the generic and specific features of the invention herein described and all statements of the scope of the invention which, as a matter of language, might be said to fall therebetween.

I claim:

1. In a valve, the combination of a fixed structure presenting a valve port and an encircling substantially uniplanar surface including a valve-seat, and a valve closing structure movable in a line substantially perpendicular to such plane, said valve closing struc- 130

ture including a support and a valve-head presenting a substantially uniplanar surface, means for floatingly mounting the valve-head on said support and maintaining the last-mentioned surface substantially parallel to the similar surface of the fixed structure as the valve is about to be closed, a flexible sealing element having relatively sharp edges on opposite sides, and means for holding the element with some looseness on the valve-head so that the valve is fully closed by squeezing said element between, and said edges tight against, the uniplanar surfaces of the two structures.

2. In a valve, a stem, a valve-head on said stem and rockably mounted thereon, a flexible ring-shaped sealing element, means for retaining the element on the head while permitting a part of the element to move relative to another part thereof, said ring being shaped to present a sharp edge beyond the head and in substantially a single plane perpendicular to the axis of the stem, and a fixed structure carrying opposite said plane and substantially parallel thereto a substantially flat surface for engaging said edge by line contact when the valve is closed, said fixed structure having a port surrounded by the line of contact of said edge and surface when the valve is closed.

3. In a valve, the combination of a valve head, a fixed port-carrying structure, a valve-closing member carried by said valve head comprising a ring of hard elastic material having a sharp edge facing said fixed structure, said fixed structure having a surface surrounding the port and contained in a plane substantially parallel to the plane of said edge, means for giving a closing movement to said valve-head along a line perpendicular to said planes, and means for retaining the closing member on the valve-head to insure contact between said edge and the fixed structure within the confines of said surface, while permitting parts of said member to be flexed as said closing movement nears completion.

4. In a valve, the combination of a movable valve-head, a fixed structure forming part of the valve casing and having a through port, said head and the fixed structure each carrying substantially flat surfaces, the surface on the fixed structure encircling the port, means for guiding the direction of travel of the head during closing of the valve to maintain said surfaces substantially parallel yet variable from parallelism within given limits, a valve-closing ring of flexible material shaped to present sharp edges at opposite faces of the ring, the straight line which cross-sectionally of the ring joins said edges being substantially parallel to the direction of travel of the valve-head under control of said guiding means, and a ring-retaining means on the head for holding the ring for travel with the head while holding the ring edges and the surface on the head substantially parallel yet

variable from parallelism within given limits.

5. A valve-closing member for interposition between opposed surfaces on relatively movable valve parts, comprising a ring of hard elastic material and having a cross section substantially diamond shaped but with one corner flattened to form a fifth face.

6. In a valve, the combination of a valve-head and a fixed valve-seat structure toward and away from which the head is movable, said head and structure carrying annular substantially flat and parallel surfaces, means for holding said head to a line of travel substantially perpendicular to said surfaces, a ring-shaped sealing member of hard elastic material carrying sharp edges for biting tight against both surfaces when the valve is fully closed, and means for retaining the member on the head.

7. In a valve, the combination of relatively movable valve-head and valve-port structures, a flexible valve-closing member to be clamped tight between said structures to close the valve against high pressures, means for insuring such tight closure including a surface carried by the valve-port structure, said member having a sharp edge to coact with a part of said surface, said member being mounted in one of said structures so as to permit a grit-plowing action of said edge during closing of the valve.

8. In a valve, the combination of a structure forming part of the valve casing and having a port surrounded by an annular surface, said structure also being shaped to provide a chamber opening away from the port mouth so that a bottom for said chamber is formed by said surface, a valve-closing structure, a valve-sealing element carried by said structure, said valve-closing structure being movable at right angles to the plane of the port mouth to position said element to contact with said surface to cause closing of the valve, the walls of said chamber and the walls of the valve closing structure being so shaped and related to each other that during movement of said element toward contact with said surface, the passage between said walls for the valve-traversing fluid will decrease in cross-sectional area toward the mouth of said port, said valve-closing structure including a part adjacent to and surrounding said element and another part of greater cross-sectional area loosely slidable in said chamber during closing movement of the valve-closing structure.

9. In a valve, the combination of a structure forming part of the valve casing and having a port surrounded by an annular surface, said structure also being shaped to provide a chamber opening away from the port mouth so that a bottom for said chamber is formed by said surface, a valve-closing structure, a valve-sealing element carried by said structure, said valve-closing structure being

- movable at right angles to the plane of the port mouth to position said element to contact with said surface to cause closing of the valve, the walls of said chamber and the walls of the valve closing structure being so shaped and related to each other that during movement of said element toward contact with said surface, the passage between said walls for the valve-traversing fluid will decrease in cross-sectional area toward the mouth of said port, said valve-closing structure including a part adjacent said element of less cross-sectional area and a part thereabove of greater cross-sectional area, the latter part shaped to slide within the chamber loosely during closing movement of the valve-closing structure.
10. A valve whereof the casing has inlet and outlet ports and wherein said casing is shaped to provide a passage through the valve and to present a part of said casing as an impact and change-direction surface intermediate said ports for a high velocity high pressure fluid, said surface being carried by the casing wall and being of greater thickness than the walls of the casing which guide the fluid toward and away from said surface.
11. The valve defined in claim 10, wherein the walls last-mentioned are imperceptibly blended with the wall carrying said surface, as the result of gradual increases of thickness of the surface-carrying wall and gradual decreases of thickness of each of the other walls.
12. A valve comprising a casing having a discharge passage formed therein and a flat valve seat surrounding the discharge passage, a cylindrical wall surrounding and extending above the seat, the surface of the cylindrical wall being curvingly merged into the surface of the seat.
13. A valve comprising a casing having a discharge passage formed therein, a removable element secured to the casing and formed with a discharge port in alinement with said discharge passage, the removable element being formed with a flat valve seat surrounding said discharge port, a cylindrical wall formed on the removable element surrounding and extending above the seat, the surface of the cylindrical wall being curvingly merged into the surface of the seat.
14. A valve comprising a casing having a discharge passage formed therein, a removable element secured to the casing and formed with a discharge port in alinement with said discharge passage, the removable element being formed with a flat seat surrounding the port and with a cylindrical wall surrounding and extending upwardly and lying wholly above the seat, and a valve head adapted to fit into close proximity to the cylindrical wall, said head carrying a part adapted to form a seal against said seat.
15. A valve comprising a casing having a discharge passage formed therein, a removable element secured to the casing and formed with a discharge port in alinement with said discharge passage, the removable element being formed with a flat seat surrounding the port and with a cylindrical wall surrounding and extending upwardly and lying wholly above the seat, and a valve head adapted to fit into close proximity to the cylindrical wall, said head carrying a part adapted to form a seal against said seat.
16. A valve comprising a casing having a discharge passage formed therein, a seat surrounding the discharge passage, a cylindrical wall surrounding and extending above the seat, a valve stem, a head carried by the stem, a restricting wall carried by the head and adapted to fit loosely within the cylindrical wall of the casing, an annular face formed on the head below the restricting wall, and a sealing member projecting from the annular face and spaced inwardly from the restricting wall, the sealing member being adapted to form a seal against the aforesaid seat.
17. A valve head structure comprising a stem, a head carried by the stem, an annular face formed on the lower side of the head, a circular flange projecting from an intermediate part of the annular face, a sealing ring within the flange, said sealing ring having a flat face engaging the inner side of the circular flange, a sharp corner next to the annular face, a sharp corner extending away from the annular face and projecting below the flange, and means for holding the sealing ring in position.
18. A valve head structure comprising a stem, a head carried by the stem, an annular face formed on the lower side of the head, a circular flange projecting from an intermediate part of the annular face, a sealing ring of hard elastic material within the flange, and means for holding the sealing ring loosely in position for contacting with the annular face and with the inner side of the circular flange.
19. A sealing member for interposition between opposed surfaces on relatively movable valve parts comprising a ring having a sharp upper edge, a sharp lower edge directly below the upper edge, and an outer peripheral surface substantially parallel to a line joining the upper and lower edges.
- In testimony whereof I affix my signature.
- WYLIE G. WILSON.
